ROLLER FOR A PAINT ROLLER

Esther C. Watzulik, Cleveland, Ohio, assignor to The Sherwin-Williams Company, Cleveland, Ohio, a corporation of Ohio

Application February 27, 1956, Serial No. 40,365

Term of patent 14 years

(Cl. D9—2)

Fig. 1

Fig. 2

Fig. 1 is a perspective of a roller for a paint roller embodying the ornamental design.

Fig. 2 is a development of the roller showing the full surface of the roller shown in Fig. 1.

I claim:

The ornamental design for a roller for a paint roller, substantially as shown.
